FOUNTAIN TOOTHBRUSH

Diman B. Eaton, Salem, N. H.

Application June 7, 1940, Serial No. 339,381

1 Claim. (Cl. 15—136)

This invention appertains to new and useful improvements in fountain brushes and more particularly to a liquid dentifrice containing toothbrush.

The principal object of the present invention is to provide a toothbrush wherein the handle is utilized as a container for dentifrice and from which dentifrice can be dispensed to the toothbrush bristles in a convenient and sanitary manner.

Other objects and advantages of the invention will become apparent to the reader of the following specification.

In the drawing—

Figure 1 represents a side elevational view of the brush.

Figure 2 is a top plan view.

Figure 3 is a longitudinal sectional view taken substantially on the line 3—3 of Figure 2.

Figure 4 is a fragmentary enlarged sectional view through the head of the brush showing the dispensing tube.

Figure 5 is a side elevational view of the refill cartridge.

Figure 6 is an enlarged fragmentary detailed sectional view taken substantially on the line 6—6 of Figure 5.

Referring to the drawing wherein like numerals designate like parts, it can be seen that numeral 5 represents a brush head having the outstanding bristles 6, while numeral 7 denotes a cylindrical shaped handle of elongated extent and having an open butt end.

The handle 7 is hollow and communicates with the duct 8 extending longitudinally in the head 5 at a tapering seat 9 where the inside of the handle 7 constricts to merge with the duct 8.

The head 5 is formed with a bore 10 at right angles to the duct 8 and meeting the outer end thereof, this bore being adapted to receive the inner end of a flexible tube 11 which extends into the bristles 6. The outer end of this tube 11 is constricted but formed with a slit 12 through which toothpaste from the refill cartridge 13 can flow when pressure is exerted on the content of the cartridge.

The cartridge consists of an elongated tube 14 having a conical-shaped end 15. This conical-shaped end 15 has a small orifice 16 in the apex 50

thereof, which is closed by a cap 17 when the cartridge is for sale on the market.

The other end of the tube 14 is formed with a circumferentially extending channel 18 for receiving the inwardly disposed rib 19 on a compressible rubber cap 20.

The cartridge is sold on the market as shown in Figure 5 and is of such diameter as to very snugly fit frictionally in the handle 7, so that no additional securing means will be necessary. The cartridge is filled by removing the resilient cap 20 and pouring the dentifrice into the cartridge.

Obviously compression of the cap 20 will result in discharge of the liquid dentifrice from the tube 14, through the duct 8 and the tube 11, expanding the slit end of the tube 11 to permit escape to the bristles 6 of the brush.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

A toothbrush comprising a hollow handle, a brush head extending from one end of the handle, said head having a valved duct extending from the bristle side of the head to communicate with the adjacent end of the hollow handle, said hollow handle being formed with a tapered seat at the point where the duct communicates with the interior of the handle, an elongated liquid dentifrice containing cartridge frictionally fitting in the handle and being provided with a tapered discharge end snugly seated against the tapered seat in the handle, said cartridge being of a length allowing the opposite end portion of the same to protrude beyond the free end of the hollow handle when the tapered end of the cartridge is snugly seated against the seat of the handle, and a cylindrical compressible cap overlapping the protruding end portion of the cartridge and being of an external diameter equivalent to the external diameter of the hollow handle, said cap being free from connection with the handle whereby said cartridges may be pulled out of the handle by grasping said cap.

DIMAN B. EATON.
